UNITED STATES PATENT OFFICE.

PHILEMON O. DICKINSON, OF NEWARK, NEW JERSEY, ASSIGNOR TO UNGER BROTHERS, OF SAME PLACE.

DESIGN FOR A BACK FOR BRUSHES, &c.

SPECIFICATION forming part of Design No. 26,273, dated November 17, 1896.

Application filed October 10, 1896. Serial No. 608,527. Term of patent 3½ years.

To all whom it may concern:

Be it known that I, PHILEMON O. DICKINSON, a citizen of the United States, residing at Newark, in the county of Essex and State of New Jersey, have invented and produced a new and original Design for Backs of Brushes, of which the following is a description, reference being had to the drawing accompanying and forming a part of the same.

The general outline of the back is that of a flattened ellipse.

At the upper end of the back is located a pearl shell A, supported by the combined flower and scroll mass B, which together cover practically the whole surface of this end of the brush. At the lower end of the brush is located the pearl foliate figure C, which is supported by the flower and scroll-embel-

lished shield-design D, these ornamentations covering practically the lower end surface of the handle. Near the middle of the brush are located two reverse scrolls E and F, the former of which springs from the leaf-scroll G, and both bend toward each other and massing with the support B inclose the plain surface I.

The essential features of design are those above set forth.

What is claimed as new is—

The design for backs of brushes and similar articles, substantially as shown and described.

PHILEMON O. DICKINSON.
